(57) CLAIM

The ornamental design for a CPR apparatus, as shown and described.

DESCRIPTION

Reference is made to the utility patent application entitled Manual CPR Apparatus with Force Multiplier with the inventors Chris W. Cicenas and Thomas E. Lach, 61/208,849, filed on the same date as the present application, the disclosure of which is incorporated here.

This invention was made under a contract with an agency of the United States government. The name of the U.S. agency and the government contract number are: National Institute of Health contract number R41 HL071378.

FIG. 1 is a front, right perspective view of a CPR apparatus showing the new design. The belt shown in phantom represents environmental subject matter and does not form part of the claimed design.

FIG. 2 is a right elevational view thereof. The left elevational view is identical to this view.

FIG. 3 is a front elevational view thereof. The rear elevational view is identical to this view.

FIG. 4 is a top plan view thereof; and,

FIG. 5 is a bottom plan view thereof.
